UNITED STATES PATENT OFFICE.

JOHN L. ALKIRE, OF DENVER, COLORADO.

PENCIL-SHARPENER.

1,188,379.

Specification of Letters Patent. Patented June 27, 1916.

Application filed January 22, 1915. Serial No. 3,777.

To all whom it may concern:

Be it known that I, JOHN L. ALKIRE, a citizen of the United States, residing at Denver, in the county of Denver and State 5 of Colorado, have invented certain new and useful Improvements in Pencil-Sharpener, of which the following is a specification.

This invention relates to pencil sharpeners and more particularly to sharpeners of 10 the type shown and described in United States Letters-Patent No. 1119788, issued to me on December 8, 1914.

The principal object of the present invention resides in the provision of means for 15 retaining the cutting member of the device removably against longitudinal displacement on the sheath member of the same.

Another object of the invention is to form 20 on the cutting member, longitudinal flanges which prevent its transverse displacement on the sheath member, facilitate its insertion into the same, and at the same time provide auxiliary cutting edges for sharpening the graphite of the pencil after its wood 25 has been removed.

An embodiment of my invention has been shown in the accompanying drawings in the various views of which like parts are similarly designated, and in which,

30 Figure 1 is a plan view of my improved pencil sharpener drawn to an exaggerated scale, Fig. 2, a longitudinal section of the same taken along the line 2—2, Fig. 1, Fig. 3, a fragmentary elevation of the end of the 35 sharpener at which its chisel or cutting member is disposed, Fig. 4, a transverse section along the line 4—4, Fig. 1, and Fig. 5, a perspective view of the cutting member, likewise drawn to an exaggerated scale.

40 Referring to the drawings by numerical reference characters, 2 designates the sheath member of the device made of brass or other suitable material, into which in practice the pencil is inserted, and 3 the cutting member which is removably secured on the sheath as will hereinafter be more fully described.

The present invention resides more particularly in the construction of the cutting 50 member 3 which as in the form shown in the hereinbefore mentioned patent, is composed of an elongate blade of tempered steel which at one of its ends is sharpened to provide a cutting edge, and which at its 55 opposite end is curved or rolled to provide a thumb rest.

The cutting member made in accordance with the present invention, has furthermore, means to removably retain it on the sheath against longitudinal displacement to which 60 it is subject by reason of the pressure exerted when a pencil is drawn across its sharpened end.

The improved cutting member has, furthermore, means which facilitate its insertion in the sheath, prevent its transverse displacement, and at the same time provide cutting edges separate from that above-mentioned for sharpening the graphite of a pencil after the wood has been cut away.

The sheath like that shown in the patent, is of cylindrical form and open at its ends. It has a longitudinal slot the edges of which are formed and bent to provide three pairs of oppositely disposed lips 4, 5 and 6 which 75 coöperate to secure the cutting member in its operative position, and a mouth 7 to receive the end of the pencil which is being pointed.

One of the pairs of lips, 4, is disposed at 80 an extremity of the sheath, another pair, 6, is formed adjacent the mouth of the same, and the third pair of lips, 5, is disposed intermediate of the others in a plane nearer the axis of the sheath to provide a support 85 for the cutting member placed beneath the outer pairs. The sheath is furthermore provided with a spring 8 which is formed opposite to its slot by parallel, longitudinal incisions and which is bent inwardly to gently 90 press the pencil toward the cutting edge of the chisel 3.

The blade of the cutting member is curved transversely as at 9 and it has at its longitudinal edges two flanges 10 which lie in a common plane at an angle to its curved portion. The curved portion of the member is sharpened at one of its ends to provide the cutting edge 12 for removing the wood of the pencil, and the corresponding ends of its flanges are sharpened to provide the auxiliary cutting edges 13 for pointing the graphite of the pencil after its wood has been removed. The member has at its opposite end, a thumb rest which is formed by 100 bending or rolling the metal, as shown at 14 in the drawings.

The means for retaining the cutting member against longitudinal displacement, consists of a pair of outwardly projecting, 110 rearwardly tapering prongs 15 which are formed oppositely on the longitudinal edges

of its flanges to provide transversely alined shoulders 16.

To place the cutting member in its operative position in the sheath member, its flanges are slid longitudinally underneath the lips 4 and 6 and over the lips 5.

When during the sliding motion of the member the slanting edges of the prongs on its flanges engage the end of the sheath, the latter, which is made of resilient material, will spread to permit of the prongs moving underneath the lips 4 until they pass the inner ends of the same when the sheath will naturally resume its normal curvature.

15 The position of the shoulders 16 on the cutting member with relation to the ends of the lips 4, securely locks the member against rearward motion when the pencil to be pointed is drawn across its cutting edge 12. 20 This feature of my invention has been found to be of great value in the operation of the article by virtue of the fact that persons not proficient in its use often fail to place the thumb against the rest 14 of the cutting member, and thereby cause its displacement during the cutting action.

When it is desired to remove the member 3 for the purpose of sharpening its cutting edges, the end of the sheath is spread by the insertion of a suitable wedge until the lips 4 are separated to disengage the shoulders 16 on the cutting member.

When the member 3 is in its operative position on the sheath, its sharpened end-edge 35 projects beyond the ends of the lips 6 so that when a pencil is inserted slantingly into the sheath, it will when drawn rearwardly, engage the cutting edge of the curved portion of the chisel which in consequence re- 40 moves the wood.

By turning the pencil repeatedly during its lengthwise motions, the wood is rapidly formed into a tapering point which exposes the graphite at the end of the pencil.

45 To point the exposed graphite, the end of the pencil is drawn across one of the cutting edges 13 of the flanges 10. In this connection it should be understood that it has been found difficult to sharpen the graphite by drawing it across the curved cutting edge 12 of the cutting member, without breaking, unless more care is exercised than is usually taken by the average purchaser of an article of this character.

55 The flanges 10 besides facilitating the insertion of the cutting member, serve when placed under the lips 4 and 6 and upon the lips 5 of the sheath member, to securely hold

the cutting member against transverse displacement.

The upper surface of the cutting member may be provided with a series of sharp ridges as indicated at 17 to provide a file for sharpening the graphite of the pencil to a fine point.

Having thus described my invention what I claim and desire to secure by Letters-Patent is:

1. A pencil sharpener comprising a sheath-member having guide-ways in the same plane and a transversely curved cutting-member sharpened at one of its ends and having its longitudinal edges bent into said guide-way.

2. A pencil sharpener comprising a sheath-member having guide ways in the same plane and transverse shoulders, and a transversely curved cutting member having its longitudinal edges bent into said guide ways, and provided with transverse shoulders engaging the shoulders on the sheath-member.

3. A pencil sharpener comprising a sheath-member and a cutting-member slideable on said sheath-member and having a stop 85 which engages an end of the same, the said members having engaging shoulders transverse to the movement of the cutting member.

4. A pencil sharpener comprising a sheath-member having guide ways in the same plane, and transverse shoulders, and a transversely curved cutting-member having its longitudinal edges bent into said guide-ways, the said cutting member having 95 prongs tapering longitudinally relative to its said edges and formed with shoulders which engage the shoulders on the sheath-member.

5. A pencil sharpener comprising a sheath-member having guide ways in the same plane, and transverse shoulders, and a transversely curved cutting-member having its longitudinal edges bent into said guide-ways, the said cutting member having a stop 105 engaging an end of the sheath-member and prongs tapering longitudinally relative to its said edges and formed with shoulders which engage the shoulders on the sheath-member.

In testimony whereof I have affixed my signature in presence of two witnesses.

JOHN L. ALKIRE.
